UNITED STATES PATENT OFFICE.

WALTER H. SMITH, OF PITTSBURGH, PENNSYLVANIA, ASSIGNOR TO MILLER SAW-TRIMMER COMPANY, OF PITTSBURGH, PENNSYLVANIA, A CORPORATION OF PENNSYLVANIA.

SHEET-REGISTERING DEVICE.

1,419,175.

Specification of Letters Patent. Patented June 13, 1922.

Application filed January 20, 1920. Serial No. 352,856.

To all whom it may concern:

Be it known that I, WALTER H. SMITH, a subject of the King of Great Britain, residing at Pittsburgh, in the county of Allegheny and State of Pennsylvania, have invented new and useful Improvements in Sheet-Registering Devices, of which the following is a specification.

My invention relates to sheet registering devices, and especially pertains to registering devices for use in connection with platen presses, particularly those of the Gordon type.

In feeding sheets of paper or the like, especially to platen printing presses, it is usual to provide one or more end abutments and one or more side abutments on the surface to which the sheets are to be fed, these abutments being so placed that when a sheet is made to engage with an end and a side against them it will be in correct printing register with the type in the form. Devices have been from time to time produced for automatically bringing the sheet, after it has been deposited on the platen or corresponding surface, into engagement with an end and a side against such abutments. It is the principal object of my invention to improve upon automatic devices of this character and to provide a sheet registering device which will be of a simple and economical construction, efficient and accurate in operation, and capable of withstanding heavy and continuous service. Other objects will appear from the following specification and annexed claims.

By way of example, I have described one embodiment of my invention in the following specification and shown it in the accompanying drawings, in which:

Fig. 1 is a plan of the platen of a Gordon press, having applied thereto a register device constructed in accordance with my invention, the gripper bar being shown as having rocked so as to lift the gripper from the platen.

Fig. 2 is an enlarged section taken on the line 2—2 of Fig. 1, looking in the direction of the arrows;

Fig. 3 is a section enlarged further, taken on the line 3—3 of Fig. 1, looking in the direction of the arrows; and

Fig. 4 is an enlarged plan of the register

device shown in Fig. 1, in the position which it assumes when the gripper bar is rocked 55 to bring the grippers flat upon the platen.

The register device is herein described as applied to the platen of a job press of the Gordon type. Such a press includes a platen 10, rockable into and out of printing relation 60 with the type form carrying bed, and having a tympan 11 secured in a place thereon by bails 12. Mounted to rock in bearings carried by the platen 10, is a gripper bar 13 having adjustably secured thereto grippers 65 14. When the platen is in and near printing position, the grippers 14 press downwardly upon the sheet thereon, but when the platen is in position for receiving a sheet, the grippers 14, owing to the rocking of the 70 bar 13, are raised from it as shown in Fig. 1. In applying the form of my improved register device described herein, the gripper bar 13 has portions thereof cut away as at 15 and 16.

A register block 17 is applied to the center of the front of the platen and comprises a top portion 18 formed with a longitudinal groove 19 having a number of tapped holes 20 therein. Extending down from the top 80 portion 18 is a standard 21, adapted to lie closely against the front of the platen, having a flange 22 extending at right angles therefrom under the platen. The flange 22 has formed therein a pair of holes 23 which 85 are passed over stems 24, so that the flange 22 engages from below against collars 25 formed upon the stems 24 and is secured in such engagement by nuts 26, with which the stems are provided. The stems 24 have a 90 threaded connection with the platen and extend therethrough to the top surface. By adjusting the stems in the platen the position of the collars 25 relative to the top surface of the register block 17 may be adjusted 95 to meet requirements.

The register device herein described comprises a base 27 formed with a tongue 28 to engage the groove 19 of the register block, to which latter the base is secured by means 100 of a screw 29 entering one or another of the holes 20. Extending upwardly and rearwardly from the base 27 is an arm 30 formed at its end with a socket in which is secured a pin 31. Mounted to rock upon the pin 31 105 is a short lever 32 formed with downwardly

extending flanges 33 and having a tail piece 34 extending at an angle therefrom and lying upon the upper part of the gripper bar 13 and beneath a bail 25 secured to the 5 rear of the latter.

Pivotedly mounted on the base 27 is an arm 36 having its end 37 bent downwardly and then back upon itself at 38, the inner end of the portion 38 being spaced from 10 the portion 37 by posts 39. Within the socket thus formed is a plate 40, having its ends upturned to prevent displacement, operated on by a screw 41. In use, the shank of a register finger is inserted in the socket, 15 beneath the plate 40, and is clamped in position therein by tightening the screw 41.

To the arm 36 is pivoted, intermediate the end 37 and the pivot about which the arm swings, one end of a link 42, the other 20 end of this link being pivoted to the flat head 43 of a pin 44 rockably mounted between the flanges 33 of the short lever 32. The effect of this connection between the arm 36 and the short lever 32 is that as the 25 gripper bar 13 rocks from the position shown in Fig. 1 to the position shown in Fig. 4 the link 42 will be pulled to the rear, thus causing the arm to swing rearwardly about its pivot.

Secured in the socket at the end of the arm 36 is the shank of a register finger 45 which has at its end a sheet receiving fork 46. A sheet 47 is indicated in full lines in Fig. 1, engaging in the fork 46 in an out-of-register 30 position such as it might assume in being fed to the platen. The feeding of the sheets takes place when the register finger and other parts are in the position shown in Fig. 1. After a sheet has been fed, the platen begins to rock toward printing position, and 35 the gripper bar 13 to rock toward the position shown in Fig. 4. This movement of the gripper bar results in the arm 36 being pulled back by the link 42, whereby the register 40 fork is caused to rock in the arc of the circle having the pivot of the arm 36 as its center. In this manner the register fork and sheet 47 are brought into the position shown 45 in dotted lines in Fig. 1, with one side and an end of the sheet in engagement with the 50 end register abutments and side register abutments, indicated in the drawings as end register pins 48 and a side register pin 49. Perfect register is thus obtained.

The register device described above is of an exceedingly simple construction, and can be produced at a low cost. It consists of a 55 relatively few parts, which latter are of a rugged nature and well able to withstand the hard and continuous usage to which such a device is subjected. The device moreover, can be depended on to perform perfectly the 60 function of bringing the sheet into correct engagement with the end and side register abutments.

I have given above a detailed description of one form of register device embodying my invention; but I wish it understood that changes may be made therein without exceeding the scope of the invention, what I 70 claim being:

1. A sheet registering device comprising a member for pivotal connection with a sheet support, a sheet engaging member adjustably connected with said first named member, and means engaging said first named member between its pivot and said second named member, for rocking said first named member about its pivot, thereby to bring a sheet engaged by said engaging member into 80 registered position. 75

2. A sheet registering device comprising a member for pivotal connection with a sheet support, said member having a socket associated therewith, a sheet engaging member 85 adjustably mounted in said socket, and means, engaging said first named member between its pivot and said socket, for rocking said first named member about its pivot, thereby to bring a sheet engaged by said engaging 9 member into registered position.

3. The combination with a printing press platen having a rocking bar, of a sheet registering device comprising a support for rigid connection with said platen, a member 95 pivoted directly to said support, a sheet engaging member adjustably connected with said first named member, and means, connected with said rocking bar, for rocking said member about its pivot, thereby to 100 bring a sheet engaged by said engaging means into registered position. 105

4. The combination with a printing press platen, having a rocking bar, of a sheet registering device comprising a support for rigid connection with said platen, a member pivoted directly to said support, said member having a socket associated therewith, a sheet engaging member adjustably mounted in said socket, and means, connected with 110 said rocking bar, for rocking said first named member about its pivot, thereby to bring a sheet engaged by said engaging means into registered position. 115

5. The combination with a printing press platen, having a rocking bar, of a sheet registering device comprising a member for pivotal connection with said platen, a sheet engaging member adjustably connected with 120 said first named member, and means, connected with said rocking bar and engaging said first named member between its pivot and said second member, for rocking said first named member about its pivot, thereby to bring a sheet engaged by said engaging 125 means into registered position.

6. The combination with a printing press platen having a rocking bar, of a sheet registering device comprising a member for pivotal connection with said platen, said mem- 130

- ber having a socket associated therewith, a sheet engaging member adjustably mounted in said socket, and means, connected with said rocking bar, and engaging said first 5 named member between its pivot and said socket, for rocking said first named member about its pivot, thereby to bring a sheet engaged by said engaging means into registered position.
- 10 7. A sheet registering device comprising a support for attachment to a platen adjacent an edge thereof, a base mounted upon said support so as to be movable longitudinally thereof, a member directly pivoted to said 15 base and having sheet receiving means as- sOCIATED therewith, and means for rocking said member about its pivot.
8. A sheet registering device comprising a base for attachment to a platen, a foot pivoted to said base for cooperative connection 20 with the gripper bar of said platen, and arm directly pivoted to said base and having sheet receiving means associated therewith, and means for connecting said arm with said foot.
